(57) **CLAIM**

The ornamental design for a kitchen implement handle, as shown and described.

DESCRIPTION

FIG. 1 is a front, perspective view of a kitchen implement handle showing our new design;

FIG. 2 is a front view thereof, rear view being a mirror image of the front view;

FIG. 3 is a right side view thereof, the left side view being a mirror image of the right side view;

FIG. 4 is a top view thereof; and

FIG. 5 is a bottom view thereof.

FIG. 6 is a front, perspective view of the kitchen implement handle of FIG. 1 illustrated with additional subject matter in broken lines per one example of use of the kitchen implement handle;

FIG. 7 is a front view thereof;

FIG. 8 is a rear view thereof;

FIG. 9 is a right side view thereof, the left side view being a mirror image of the right side view;

FIG. 10 is a top view thereof; and

FIG. 11 is a bottom view thereof.

FIG. 12 is a front, perspective view of the kitchen implement handle of FIG. 1 illustrated with additional subject matter in broken lines per one example of use of the kitchen implement handle;

FIG. 13 is a front view thereof;

FIG. 14 is a rear view thereof;

FIG. 15 is a right side view thereof, the left side view being a mirror image of the right side view;

FIG. 16 is a top view thereof; and

FIG. 17 is a bottom view thereof.

The features shown in broken lines are portions of the kitchen implement handle or environmental subject matter to the kitchen implement handle forming no part of the claimed design. The features shown in long dash-short dash bolded broken lines indicate the bounds of the claimed design and otherwise form no part of the claimed design.
